(57) **CLAIM**

The ornamental design for channels, treads and reservoir for vehicle floor mat or tray, as shown and described.

DESCRIPTION

FIG. 1 is a perspective view of channels, treads and reservoir for vehicle floor mat or tray, showing my new design;

FIG. 2 is another perspective view thereof;

FIG. 3 is a top view thereof;

FIG. 4 is an enlarged section view taken line 4—4 of FIG. 3;

FIG. 5 is an enlarged section view taken along line 5—5 of FIG. 3; and,

FIG. 6 is an enlarged section view taken along line 6—6 of FIG. 3.

The back and external sides of the vehicle floor tray or mat into which my design is incorporated are unadorned and form no portion of the design.

The broken line showing of environment is for illustrative purposes only and forms no part of the claimed design.
